INVENTOR
SYLVESTER A. SOMMERS

BY *George B. Willcop.*
ATTORNEY

UNITED STATES PATENT OFFICE

SYLVESTER A. SOMMERS, OF FRANKENMUTH, MICHIGAN, ASSIGNOR TO SOMMERS BROS. APPLIANCE CO., OF SAGINAW, MICHIGAN

STOOL

Application filed November 18, 1929. Serial No. 407,910.

This invention relates to stools especially adapted for convenient use in kitchens, laundries and other places where drying or airing of fabrics is done.

5 The object of the invention is to provide a stool that can be made of sheet metal, strong and attractive in appearance, yet inexpensive to manufacture; to provide a seat member for the stool adapted to serve the usual 10 purposes of a stool and also arranged to be available as a portable drying and airing rack for articles being laundered, so they can be placed near a stove or heater and can be turned about as required for complete and 15 rapid drying or airing.

Another object is to provide a stool that can be used by the operator at a mangle as a convenient rack on which to hang the freshly ironed articles.

20 A further object is to provide means for stowing the drying rods when not in use, so they will remain in compact form when the device is used merely as a stool.

With the foregoing and certain other objects in view, which will appear later in the specification, the invention comprises the devices described and claimed and the equivalents thereof.

In the drawings Fig. 1 is a side view, partly 30 broken away, of a stool embodying my invention.

Fig. 2 is a top plan view.

Fig. 3 is a transverse section through the seat.

35 Fig. 4 is a plan view showing a modified form of seat plate.

As is clearly shown in the drawings the stool consists in the legs 1, casters 2 and the shelf 3 fixed to the legs 1 and formed with a 40 central aperture 4.

A seat is secured to the legs by spot welding, or otherwise and comprises a plate member 5 formed with a downwardly extending peripheral flange 6 and having depressions 45 7 formed in it near its flanged margin. These depressions may take the form of a peripherally disposed groove 7a, as shown in Fig. 4, or they may be individual cups or depressions, as shown in Fig. 2.

50 The depressions 7 or 7a have their bottoms

formed with apertures 8 spaced apart circumferentially as shown. A rod 9 is slidably received in each aperture. Each rod has an end 10 formed to present an offset, in known manner. The other end of the rod is 55 formed with a knob 11.

When the article is used as a stool the rods 9 are held suspended by their knobs 11 which are received in the depressions 7 so as to be flush with the seat plate 5. The offset ends 60 of the rods are bunched together and held against swaying and rattling by being received in the central aperture 4 of shelf 3.

When used as a drying rack one or more of the rods 9 are pulled up through the aperture 65 8 and its offset end is hooked under the marginal edge of the aperture and rests on the rim of the plate 5 above the flange 6 which serves as a reinforcing member to support the rod in horizontal position. 70

When the stool is being used, for example, in front of a mangle, the operator sits on the stool and uses some of the rods as a convenient cooling rack within easy reach.

When a large article, such as a table cloth, 75 is to be treated for removal of stains it can be spread on top of the extended arms, the bowl of cleaning material being placed underneath it on the stool.

By the means above described I have produced a simple and inexpensive and very convenient article of manufacture that is well adapted for many uses in the kitchen or laundry and for similar situations. 80

Having thus described my invention, what 85 I claim and desire to secure by Letters Patent is:

1. A stool including a seat plate having a peripheral flange, said plate having depressions formed therein adjacent the flange, the 90 bottoms of said depressions having apertures therein spaced apart circumferentially, a rod slidably received in each aperture, an end of said rod formed with an offset, the other end formed with a knob, for the purposes 95 set forth.

2. A structure as set forth in claim 1 wherein the rods when in depending position are held by a centrally apertured shelf fixed to the legs of the stool below the seat thereof. 100

3. A stool including a seat plate having a peripheral flange, said plate having depressions formed therein adjacent the flange, the bottoms of said depressions having apertures therein spaced apart circumferentially and a rod slidingly received in each aperture.
4. A structure as set forth in claim 1 where-in the rods when in depending position are held by a centrally apertured member fixed 10 to the legs of the stool below the seat thereof.
5. In a stool including supporting legs and a seat member thereon formed of sheet metal shaped to present apertured depressions disposed around the seat member near its periphery, and rods loosely received in said apertures and provided at their ends with means adapted to engage the bottoms of the depressions and to engage the seat member near the tops of the depressions so as to hold 20 the rods releasably in outwardly projected position.
6. The combination of a stool including supporting legs and a seat thereon formed with apertures around its rim, rods received 25 loosely in said apertures and means associated with the rods for releasably holding them in position within said apertures and projecting outwardly from said seat.

7. In combination with a structure as set 30 forth in claim 6, means associated with said rods for holding them in retracted position within said apertures and depending therefrom.

In testimony whereof, I affix my signature.
35 SYLVESTER A. SOMMERS.
